United States Patent Office

Des. 221,239

Patented July 20, 1971

221,239

AERIAL TOY

David William Main, 1252 Columbia St.,
Denver, Colo. 80206

Filed Mar. 9, 1970, Ser. No. 21,789

Term of patent 7 years

Int. Cl. D21—02

U.S. Cl. D34—15

FIG. 1

FIG. 2

FIG. 3

FIG. 1 is a bottom plan view of an aerial toy showing my new design;

FIG. 2 is a top plan view thereof; and

FIG. 3 is a right side elevational view of FIG. 2, the opposite side being substantially similar.

I claim:

The ornamental design for an aerial toy, as shown and described.
